(57) **CLAIM**

The ornamental design for an adjustable ball mount adapter.

DESCRIPTION

FIG. 1 is a front top perspective view of an adjustable ball mount adapter.

FIG. 2 is a front bottom perspective view of the adjustable ball mount adapter.

FIG. 3 is a left side elevational view of the adjustable ball mount adapter.

FIG. 4 is a front elevational view of the adjustable ball mount adapter.

FIG. 5 is a rear elevational view of the adjustable ball mount adapter.

FIG. 6 is a right side elevational view of the adjustable ball mount adapter.

FIG. 7 is a top plan view of the adjustable ball mount adapter; and,

FIG. 8 is a bottom plan view of the adjustable ball mount adapter.

The broken lines shown in the drawings illustrate unclaimed portions of an adjustable ball mount adapter and form no part of the claimed design.
